TRACK MAINTENANCE TOOL

John G. Schaeufele, Fort Knox, Ky.

Application September 2, 1943, Serial No. 500,933

4 Claims. (Cl. 59—7)

(Granted under the act of March 3, 1883, as amended April 30, 1928; 370 O. G. 757)

The invention described herein may be manufactured and used by or for the Government for governmental purposes, without the payment to me of any royalty thereon.

The present invention pertains to a novel maintenance tool for use in connection with endless track of track-laying vehicles, such as combat tanks, for example. Such track consists in many cases of an endless, interconnected series of blocks. More specifically, the track for which the present tool is designed consists of blocks with pins extending from the ends, the pins of adjacent blocks being joined by an enclosing connector or clip with a tightening wedge.

In service, it is frequently necessary to replace a track block without removing the track from the vehicle. The track is ordinarily under tension on the vehicle, and the operation of reuniting the track after it has been severed requires considerable force.

The principal object of the invention is to provide a maintenance tool adapted to remove the connector when a damaged block must be removed and also, after substitution of a new block, to bring the ends together so that they may be reunited under the conditions previously described. Another object of the invention is to provide such a tool which may be operated manually, quickly and under adverse conditions of military service.

A preferred embodiment of the invention is disclosed, by way of example, in the following description and in the accompanying drawing in which:

Figure 1 is a plan view of the tool applied to the track for pulling the connector;

Figure 2 is a detail side elevation thereof;

Figure 3 is a side elevation illustrating the operation of bringing the track ends together, and

Figure 4 is a section on the line 4—4 of Figure 3.

The track in this case comprises a series of blocks 1 with pins 2 extending from the lateral edges thereof. The pins are positioned close to the meeting edges of the blocks in order to be held by a connector which serves as an articulator. The connector comprises a body 3 suitably apertured at 4 to receive a pair of pins when brought together. The body is formed with a projecting wall 5 having two curved ends 6 adapted to embrace and give further support to the pins inserted in the apertures 4. A wedge 7 is inserted between the pins and is formed with a screw 8 passed through an opening 9 in the intermediate part of the wall 5. The wedge is drawn up by a nut 10 on the screw 8. A track guide 11 extends

vertically from the body 3 and cooperates with the tool in a manner which will presently be described. This combined connector and the guide is already known in the art and does not form a part of this invention.

The tool consists of a rigid elongated body formed by a pair of spaced and parallel, elongated side plates 12 between which, at one end, is inserted a block 13 formed with an upwardly extending hook or jaw 14. The plates are secured to the block by a bolt and nut 15.

Between the remaining ends of the plates 12 is secured a bearing block 16 held by a bolt and nut 17. A screw shaft 18 disposed between the plates 12 has a blank end 19 journaled in and passing through the bearing 16. The free or exposed end of the shaft, beyond the plates 12, carries a ratchet 20 fixed thereto and a pawl lever 21 pivotally mounted thereon. The lever is operated to turn the pawl and screw in a manner well known in the art.

On the screw is threaded a sliding block or nut 22 disposed between the plates 12 and formed with a hook or jaw 23 extending outwardly therefrom and opening towards the open side of the jaw 14, as clearly shown in Figure 2. At the opposite side from the hook 23, the nut 22 has an extended bottom piece 24 carrying a pair of pins 25 lying parallel to the plates 12 and spaced apart equally to the pins 2 in the connector.

A pin 26 extends vertically downward from the bottom of the forward block 13, midway between the horizontal pins 25, and is of such size as to be received in the opening 9 of the wall 5, as will be described. A bolt 27 extends angularly upward from the forward wall of the block 13 and carries an adjustable cap screw 28, also for a purpose that will presently appear.

The operation of pulling a connector off the track is illustrated in full lines in Figures 1 and 2. The wedge 7 is first removed. The pin 26 is inserted in the opening 9, and the horizontal pins 25 engage the ends of the block pins 2. It will be understood that the tool must be dimensioned according to the track on which it is to be used. The tool is positioned so that the pins 25 are horizontal, or in alignment with the pins 2, and the cap screw 28 is adjusted to engage the guide 11. The ratchet lever 21 is then turned in the direction that would normally feed the block 22 towards the tracks. However, since the block is held stationary by the pins 26, 2 and 25, the remainder of the tool is drawn in the opposite direction, whereby the connector is pulled off the pins 2. The engagement of the cap screw 28 with

the guide 11 holds the tool from being swung upward under the force applied to the screw.

When the severed ends of the track are to be reunited, for example, after a defective block has been replaced, the screw is turned to withdraw the jaw 23 from the jaw 14 a sufficient distance to receive between them the separated pins 2'. In this case the tool lies lengthwise of the track, while in the previous operation it lay transversely, as shown in Figure 3.

The screw is now turned in the reverse direction until the pins 2' are brought to the spacing of the openings 4 in the connector. The pins 2' project axially beyond the jaws 14, 23, as shown in Figure 4, sufficiently to permit the connector body 3 to be applied thereto. The jaws are now released and withdrawn and the connector hammered back on the pins 2'. Finally, the wedge 7 is inserted in the position described and is tightened by the nut 10 on the bolt 8 thereof.

It is to be understood that there is usually one tool on each side of the track to pull the track together in a sufficiently parallel manner as to permit the end connectors to be applied to the projecting ends of the pins.

Although a specific embodiment of the invention has been illustrated and described, it will be understood that various alterations in the details of construction may be made without departing from the scope of the invention as indicated by the appended claims.

What I claim is:

1. A tool of the character described comprising a rigid elongated body, a screw mounted lengthwise thereof and rotatable therein, means for turning said screw, a fixed jaw carried by said body, a complementary jaw threaded on said screw, and a projection extending from said complementary jaw towards the fixed jaw and disposed outside of said body, said projection extending beyond the fixed jaw in the line of movement

of said complementary jaw when said complementary jaw has moved up to said fixed jaw.

2. A tool of the character described comprising a rigid elongated body, a screw mounted lengthwise thereof and rotatable therein, means for turning said screw, a fixed jaw carried by said body, a complementary jaw threaded on said screw, an anchoring pin extending from said fixed jaw and adapted to be interlocked with the work, and a projection extending from said complementary jaw towards the fixed jaw and disposed outside of said body, said projection extending longitudinally across said fixed jaw in a closed position of the tool.

3. A tool of the character described comprising a rigid elongated body, a screw mounted lengthwise thereof and rotatable therein, means for turning said screw, a fixed jaw carried by said body, a complementary jaw threaded on said screw, and a projection extending from said complementary jaw towards the fixed jaw and disposed outside of said body, and an adjustable brace extending from said fixed jaw and adapted for engagement with the work, said projection extending longitudinally across said fixed jaw in a closed position of the tool.

4. A tool of the character described comprising a rigid elongated body, a screw mounted lengthwise thereof and rotatable therein, means for turning said screw, a fixed jaw carried by said body, a complementary jaw threaded on said screw, an anchoring pin extending from said fixed jaw and adapted to be interlocked with the work, and a projection extending from said complementary jaw towards the fixed jaw and disposed outside of said body, and an adjustable brace extending from said fixed jaw and adapted for engagement with the work, said projection extending longitudinally across said fixed jaw in a closed position of the tool.

JOHN G. SCHAEUFELE.
